Primary Examiner — Ricky Pham(74) *Attorney, Agent, or Firm* — Edward S. Sherman(57) **CLAIM**

The ornamental design for a cookware lid, as shown and described.

DESCRIPTION

FIG. 1 is a top perspective view of the cookware lid, showing my new design;

FIG. 2 is a front elevation thereof;

FIG. 3 is a back elevation view thereof;

FIG. 4 is a top plan view thereof;

FIG. 5 is a bottom plan view thereof;

FIG. 6 is a right side elevation view thereof, the left side elevation view being the mirror image thereof;

FIG. 7 is a cross-sectional elevation view thereof at section line 7-7 in FIG. 4;

FIG. 8 is an enlarged cross-sectional elevation view of the portion indicated by reference number 8 in FIG. 7;

FIG. 9 is a bottom perspective view thereof; and,

FIG. 10 is a top perspective view thereof in use on a vessel that is tilted forward.

The broken lines in FIGS. 1-7, 9 and 10 are for illustrative purposes only, depicting the environment of the new design, forming no part thereof as claimed.
